UNITED STATES PATENT OFFICE.

JOHN C. FROSTEAD, OF DULUTH, MINNESOTA.

LANTERN.

1,424,293.

Specification of Letters Patent. Patented Aug. 1, 1922.

Application filed December 9, 1921. Serial No. 521,082.

To all whom it may concern:

Be it known that I, JOHN C. FROSTEAD, a citizen of the United States, residing at Duluth, in the county of St. Louis and State 5 of Minnesota, have invented certain new and useful Improvements in Lanterns, of which the following is a specification, reference being had therein to the accompanying drawing.

10 This invention relates to lanterns and has special reference to one used as a signal light by trainmen or the like.

The principal object is to produce a lantern of this character which will cast but 15 a small amount of shadow from the bottom thereof when used for signalling purposes.

Other objects and advantages of the novel structure will appear in the further description of the invention.

20 Referring to the accompanying drawing forming part of this application in which like reference characters indicate like parts:

Figure 1 is a side elevation of one of the improved lanterns showing one embodiment 25 of the invention;

Figure 2 is an enlarged vertical sectional view through the base portion of the lantern, and

Figure 3 is a horizontal sectional view on 30 the line 3—3 Figure 2.

The base or body portion 1 of the lantern is cylindrical in form and elongated vertically and made as small in diameter as possible consistent with the proper feeding of 35 the oil and housing of the wick of the lantern. There are holes or openings 2 in the opposite sides of the body portion 1 and practically midway of its ends and about which holes are securely attached as by 40 soldering or otherwise the terminals of the tubular combination handle and oil container 3. This tubular member extends gracefully upwardly and over the top of the lantern, forming a conveniently shaped 45 handle.

Within the lower end of the body member 1 and normally extending upwardly therewithin beyond the openings 2 is the adjustable sleeve 4, terminating at its lower 50 end in a closed cap like portion 5, by which it may be readily manipulated. Adjacent the cap 5, upon the circumferential wall of the sleeve, is a screw-threaded portion, indicated at 6, by which it is held within the 55 body portion 1. This screw threaded portion is designed to fit snugly so that the

sleeve may be adjusted axially within the body portion and remain in any desired predetermined position. The object of such adjustment is to provide for the possibility 60 of turning the sleeve 4 so that the larger opposed holes or openings 7 in the side walls thereof may be made to communicate with the two ends of the tubular member 3 when it becomes desirable to flood the wick chamber, or the sleeve may be adjusted a quarter turn either way so that the smaller opposed holes 8 may be made to communicate with the oil chamber, this adjustment being necessary for the normal working of the lantern. 70

Within the upper end of the body portion 1 is a screw threaded, cylindrically shaped, chambered, burner 9, through and to which the wick stack 10 is attached, it being provided with the usual means for raising and lowering the wick. About the burner chamber 9 and spaced slightly therefrom is an annular wall 11 through which are formed a plurality of air supply holes 80 12 and above these holes and formed integral with the wall 11 is an annular rim or flange 13 upon which rests the chimney 14 of the lantern. The space intermediate of the upper edge of the annular wall 11 and the wall 85 of the chamber 9 is left open so that the air coming in through the holes 12 is supplied therethrough to the interior of the lantern chimney.

Downwardly arched supporting legs 15 90 are rigidly fixed to the lower portions of the tubular member 3 adjacent the body portion 1 and the lower ends or feet of these legs, together with similarly shaped legs 16 of the guards 17, are mounted as by soldering or the like upon the annularly shaped wire 18, forming a convenient, open base for the lantern.

It will be noted that there is no external opening whatever to the tubular member 3 100 except through the body portion 1, and that the lantern has to be inverted in order to be filled which is simply accomplished by the unscrewing of the sleeve 4, and that in the event of the use of different grades of 105 signal oil the sleeve may be adjusted to the different sized openings therein, as previously described, to provide for the proper feeding of same to the wick.

Having thus described my invention, what 110 I claim and desire to secure by Letters Patent, is:

1. A signal lantern of the character described including a tubular combined handle and tank vertically surrounding the lantern.
5. 2. A signal lantern of the character described comprising in combination therewith a relatively small cylindrical body portion, a combination tubular handle and oil reservoir communicating with the body portion and vertically surrounding the lantern, substantially as described.
10. 3. A signal lantern of the character described comprising in combination a relatively small body portion, a burner mounted

upon the body portion, a combination tubular handle and reservoir communicating with the body portion and means within the latter for regulating the flow of oil to be consumed, and an open base about and extending below the body portion, substantially as and for the purpose described.

In testimony whereof I hereunto affix my signature in the presence of two witnesses.

JOHN C. FROSTEAD.

Witnesses:

S. C. BRONSON,
S. GEO. STEVENS.
